SOLVENT REFINING OF PETROLEUM OILS

Arthur W. Hixson, Leonia, N. J., and Ralph Miller,
New York, N. Y., assignors to The Chemical
Foundation, Incorporated, a corporation of Del-
aware

No Drawing. Application November 6, 1937,
Serial No. 173,194

15 Claims. (Cl. 196—13)

This invention relates to the chemical refining of petroleum oils, more particularly to the separation, by solvent extraction, of predetermined hydrocarbons from mixtures thereof with other hydrocarbons.

As is known, crude petroleum oil and pyro-
genetic fractions of such oil consist of mixtures
of different homologous groups or series of hydrocarbons, such as paraffinic, naphthenic, and
10 aromatic constituents. When petroleum oil is separated into the commercially useful fractions, such for example as gasoline, gas oil, lube oil and fuel oil fractions, the same general complexity obtains, although the respective percentages of the different groups in such commercial fractions may vary. Thus, a typical relatively high boiling range distillate, having the characteristics of lubricating oil, contains paraffinic, naphthenic, and aromatic constituents and some
15 asphalt, the respective proportions of such constituents depending largely on the type or source of the crude oil. Thus, Pennsylvania oil contains little or no asphalt and a relatively small amount of aromatics. The Coastal oil, con-
versely, has a relatively higher percentage of asphalt and aromatics than the Pennsylvania oil.

For certain uses, it is desirable to preferentially remove certain of these constituents from the homogeneous mixture, either for the purpose of improving the residuum for some special purpose or for utilizing the extracted fraction for another use. Thus, it is known that for most purposes the heavier paraffinic fractions constitute the best lubricants, especially for high temperature lubrication such as is required in the modern internal combustion engine. On the other hand, it is likewise known that the more paraffinic lighter fractions, in the gasoline range, present a decidedly greater tendency to knock than do the more olefinic gasolines. It is, therefore, sometimes desirable to treat, say, a vapor phase cracked Mid-Continent gasoline so as to preferentially extract the olefinic constituents so that
40 they may subsequently be employed to blend with other gasolines to increase the octane rating of such gasolines.

It has been proposed heretofore to subject complex mixtures of these hydrocarbon oils in the lubricating and gasoline range to the action of solvents which have a preferential affinity for the non-paraffinic constituents so as to obtain an extract and/or a raffinate respectively richer in the desired type of oil than the original stock.
55 It is known that (by choosing the proper solvent)

it is theoretically possible to preferentially dissolve the naphthenic and aromatic constituents, to segregate the solvent with its dissolved non-paraffins from the residual oil and separately to recover the residual oil or raffinate of a relatively higher paraffinicity, and an extract fraction of a relatively lower paraffinicity, than the original oil which was treated.

This result, although theoretically quite possible, has been difficult to achieve on a commercially satisfactory basis. The workers in the art have been active on this problem for over a decade and although literally hundreds of solvents or solvent mixtures have been suggested but a very few have attained commercial use. 15 Of the greater number of these extractants that have been proposed, the only ones that have gone into any substantial commercial use are; nitrobenzene, aniline, phenol, sulphur dioxide and benzene, furfural, B B' dichloroethyl ether, and 20 mixtures of cresol, phenol and propane. Each of these solvents, or solvent mixtures, present certain advantages, but they also present inherent disadvantages.

The reason why such a relatively few number 25 of solvents actually have been employed out of the vast number suggested lies in the fact that the criteria of commercial values are very difficult to meet. In the nature of its use, the quantity of the solvent employed runs into large 30 figures and actually may be calculated on a tonnage basis. For this reason the price of the solvent is a factor of dominant importance; too high a solvent cost is positively inhibitive to commercial employment, whatever may be the 35 theoretical efficacy of extraction and the theoretical recovery of the solvent, for, in actual plant operation, some solvent loss is inevitable. This factor of high cost rules out a great many otherwise satisfactory solvents, particularly the 40 more complex organic compounds.

In addition to this important factor of initial cost, there are other factors of a chemical or physicochemical nature which characterize the ideal selective solvent and which are extremely 45 difficult to discover embodied in a commercially available compound. For example, certain solvents suggested in the past, although possessing a satisfactory high selectivity, present a low solubility for the constituents which are desired to 50 be removed. In these circumstances, in order to extract such non-paraffinic constituents, a large and commercially excessive amount of such solvent must be employed. Yet again, certain solvents may possess a satisfactory selectivity and 55

possibly a reasonably high solubility for the oil to be extracted, but present some other characteristic which militates against their use. For example, such a solvent may have a density which is so close to that of the oil being treated that segregation or stratification is difficult and costly. Other factors which characterize the ideal solvent are: a desirably low melting point, a relatively low boiling point, a marked tendency to stratify from the paraffinic fraction at separation temperatures, a low solubility in water and an amenability to recovery, preferably by simple physical methods such as low temperature fractional distillation. It will thus be seen that, in the very nature of this technical use, the field from which a satisfactory selective solvent may be chosen is quite constricted.

As intimated above, one of the factors of major importance in the choice of a selective solvent is a low initial solvent cost. For refinery operations, such initial cost should, of course, be as low as possible and, in any event, should not exceed a price of the order of 9 to 10 cents a pound. Such solvent should, in conformity with the norm indicated above, have a selectivity which is as high as possible and which is at least comparable to that of the solvents now employed. Such solvent also should have a relatively high density as compared with the oils to be treated, such as a lubricating oil fraction. Additionally, the solvent should have a high miscibility temperature, a boiling point not materially exceeding 200° C. and should be substantially insoluble in water and stable under the conditions of use. A selective solvent which would satisfy these criteria would be superior to any now in commercial employment.

With the above outlined stringent requirements in mind, the prior workers naturally investigated the simple, readily available aliphatic compounds. Considered as a class, however, such compounds were found to be unsuitable. Similarly, the simpler, less expensive benzene derivatives were studied, but as indicated above, with but a very few exceptions, these were found to be ineffective. While a multitude of the more complicated derivatives have been suggested in the literature, it is apparent to those skilled in the art that the price requirement in this field is a definite limitation which rules out any such expensive synthetic derivatives.

In view of these considerations, it is apparent that if a synthetic compound is to be employed as a selective solvent, it must be produced from a starting material or mother substance that is relatively cheap and that, with this requirement, for all practical purposes the benzene derivatives, except for the simpler substitution products, are ruled out. It is also quite apparent that as an inexpensive source material petroleum products would be decidedly more preferable. In recent years the potentialities of the paraffin hydrocarbons as a source material for the production of substituted aliphatics has received considerable attention. For example, Haas and his colleagues (Ind. Chem. Soc. 28,339 (1936) and U. S. Patent 1,967,667) describe a vapor phase nitration of paraffin hydrocarbons for the production of nitro paraffins and indicate that such end products may be made available at a relatively low price. In fact, the authors point out that under this method nitrobutane may be produced at a raw material cost of about 1.8 cents per pound.

Such cheap substituted aliphatics would amply comply with the price requirements for use as a

selective solvent for the fractionation of mineral oils. The potentialities of such compounds for use as selective solvents has previously been considered and the patent literature describes the use of nitro substituted paraffins as selective solvents. An investigation of the characteristics of these simpler substitution products, however, indicates their unsuitability for the purpose at hand. As a typical example, the behavior of nitromethane is a case in point. When nitromethane (B. P. 101° C.) is mixed with an equal quantity of Mid-continent oil having a viscosity of 48 Saybolt seconds at 210° F. and a viscosity index of 57, and the mixture was heated in an attempt to insure miscibility, it was found that the solvent boiled before complete miscibility was obtained, in fact, hardly any of the oil dissolved in the solvent. This characteristic of too low a boiling point substantially precludes the use of this compound for the extraction of lubricating oils.

It might appear, theoretically, that the higher members of the series would operate, due to their higher boiling point and longer chain structure. However, this does not prove to be the case for, as the length of the chain increases, there is a corresponding decrease in density so that, while the higher homologues may satisfy the requirement as to boiling point and miscibility with the oil to be processed, the differential in density which obtains is too small to insure the necessary rapid stratification.

As the result of considerable experimentation in this field, it has been found that such cheap source material, that is to say, the paraffin hydrocarbons or their simpler derivatives, may be utilized for the production of substituted aliphatics which serve admirably as selective solvents. It has been found that as a broad proposition, while nitro substituted paraffins are unsuitable, certain derivatives are eminently suitable. Considered more specifically, it has been found that the introduction of another substituent, particularly a halogen, in the nucleus, modifies the physical characteristics of the original compound so as to render it most effective for the function of selective extraction. It was found that, when a hydrogen of a nitroparaffin was replaced with a chlorine atom, the resulting nitrochloroparaffin possessed a higher density and a higher boiling point than the corresponding nitroparaffin, and that the modification of these characteristics was of such a degree as to comply with the described criteria established for an effective selective solvent. The comparison between nitropropane, for example, and its analogue, nitrochloropropane, clearly illustrates this beneficial modification of the physical characteristics which are so important in this particular use. Whereas nitropropane has a boiling point of 131° C. and a density of 1.002 (25° C.), nitrochloropropane, on the other hand, has a boiling point of 172-3° C. and a density of 1.224 (30° C.). Similarly, whereas nitrobutane has a boiling point of 139° C. and a density of substantially .98, its analogue, nitrochlorobutane, has a boiling point of 181-8° C. and a density of 1.187 (20° C.).

It is thus clear that the marked increase in the boiling point and density is a constitutive property of the halogenated nucleus and serves to sharply differentiate the nitrochloroparaffins from the corresponding nitroparaffins in respect of their availability and utility as selective solvents.

As is known to those skilled in the art, the property of selectivity or preferential solubility

for unsaturates is constitutive and specific. In order definitely to establish the utility of this group of halogenated substituted paraffins, actual experiments were conducted, of which the following is typical.

Example I

Fifty grams of nitrochloropropene were added to 50 grams of a Mid-continent neutral oil having a viscosity of 268 Saybolt seconds at 100° F. and a viscosity index of 57.7. The mixture was heated above the miscibility temperature of 96° C. After complete miscibility had been obtained, the solution was allowed to cool, with occasional agitation, in an oven maintained at 60° C., at which temperature the two layers were separated. Each layer was then subjected to vacuum distillation.

Upon analysis (using an all-glass Fitzsimmons suspended level viscometer and calculating the yield on the weight basis), it was found that 86 per cent. of the original oil was in the raffinate and that such raffinate had a viscosity of 239.9 Saybolt seconds at 100° F. and 46.1 Saybolt seconds at 210° F. and a viscosity index of 69.1. The oil layer contained but 16 per cent. of the solvent.

It is luminously obvious that these results show that nitrochloroparaffins possess the property of marked selectivity as well as the other beneficial properties such as satisfactory boiling points, density and miscibility, which determine their commercial utility. It will be noted, in passing, that in the illustrative experiment, the yields are given in weight. Since the raffinate has a lower, and the extract a higher specific gravity than the original oil, a comparison calculated on a volume basis will be numerically more favorable.

The series of compounds which have herein been described as selective solvents may be produced in any effective or approved manner. The procedure may be by two different general methods, each utilizing the paraffins as a source material. Such paraffins may be nitrated and the resulting nitroparaffins then halogenated. Again, the paraffins may be chlorinated and the chloroparaffins may be nitrated. Then again, if desired, the compounds mentioned herein may be produced with a synthesis starting from the nitro alcohols.

For example, according to one method (see Konawaloff, Russian Journal of Physical Chemistry, 36, 22 (1904)) isobutyl chloride may be reacted with dilute nitric acid in a sealed tube at 70 to 80° C., from 12 to 16 hours and the unreacted chlorobutane separated and treated with additional amounts of nitric acid. The formed nitrochlorobutane may be removed by fractional distillation. Or again, the nitrochloroparaffin may be prepared by the method outlined by Henry (Bul. Societe Chemique de Paris, 3rd Series, 13, 999 (1885)), which consists essentially in producing a nitro alcohol by condensation of the corresponding aldehyde with a nitromethane group in the presence of a small amount of potassium carbonate, followed by the treatment of the nitro alcohol with phosphorus pentachloride to produce the nitrochloroparaffin.

A modification of the Henry method was utilized with good results. Under the Henry synthesis, in the first stage of the reaction, the nitro alcohol is obtained in yields of about 60 per cent. In the second stage, however, i. e., in the production of the chlorine substitution product, the yields are quite small. It was found that these yields could be increased considerably by diluting the nitro alcohol with dichloromethane and

dry pyridine and utilizing this chloride as the chlorinating agent. When utilizing this modified reaction, it is advisable to add the chloride slowly to the boiling mixture. The reaction products are preferably purified by washing with water and then with a dilute sodium bicarbonate solution. The dichloromethane may be removed by distillation and the nitrochloroparaffin distilled.

It will be understood that the methods given are merely suggestive and are not given as necessarily related to the actual extraction of the oil. The invention is available for employment with the described class of compounds, or their equivalents, however such compounds may be produced.

It will be appreciated that within the broad concept of the invention a relatively large number of different specific compounds may be used, the choice of which will depend on the conditions of the particular extraction operation and/or on the characteristics of the oil fraction which is to be treated. The different solvents comprehended herein may be used alone or in admixture with each other or with specifically different solvents. Again, the improved solvents described herein may be used in conjunction with other known solvents for sequential extractions.

It is particularly to be observed that the improved results disclosed herein are obtainable with the broad class of compounds described and are not limited to the particular compound cited in the example. As examples of other characteristic members of the group may be mentioned, chloronitromethane, bromo nitromethane, a-a-chloronitroethane, a-b-chloronitroethane, a-a-dibromonitroethane, a-a-chloronitropropane, a-a-bromonitropropane, a-chloro-b-nitropropane, a-chloro y-nitro propane, b-b-chloronitropropane, and the like.

While preferred modifications of the invention have been described, it is to be understood that these are given to illustrate the fundamental concept of the invention, that is the utilization of a cheap source material such as the paraffin hydrocarbons for the production of nitrogen and halogen containing substitute products which are efficacious as selective solvents for the fractional extraction of mineral oils.

We claim:

1. In the process of solvent refining of petroleum oils containing paraffinic and non-paraffinic constituents, the step consisting in separating the constituents by extracting with a nitrochloroparaffin.

2. The process of solvent refining of petroleum oils containing paraffinic and non-paraffinic constituents, which comprises selectively extracting the non-paraffinic constituents with a halogen substituted nitroparaffin.

3. The process of solvent refining of petroleum oils containing paraffinic and non-paraffinic constituents which comprises, separating such constituents by extracting the oil with a halogenated nitrogen-containing paraffin.

4. In the process of solvent refining of petroleum oils containing paraffinic and non-paraffinic constituents the step consisting in separating the constituents by extracting with a halogenated mononitroparaffin.

5. The process of solvent refining of petroleum oils containing paraffinic and non-paraffinic constituents which comprises separating such constituents by extracting the oil with a chlorinated nitrogen-containing paraffin.

6. The process of solvent refining of petroleum

- oils containing paraffinic and non-paraffinic constituents which comprises, separating such constituents by extracting the oil with a chlorinated mononitroparaffin.
5. 7. The process of solvent refining of petroleum oils containing paraffinic and non-paraffinic constituents which comprises separating such constituents by extracting the oil with a halogenated nitroethane.
10. 8. The process of solvent refining of petroleum oils containing paraffinic and non-paraffinic constituents which comprises separating such constituents by extracting the oil with a halogenated nitropropane.
15. 9. The process of solvent refining of petroleum oils containing paraffinic and non-paraffinic constituents which comprises separating such constituents by extracting the oil with a halogenated nitrobutane.
20. 10. The process of solvent refining of petroleum oils containing paraffinic and non-paraffinic constituents which comprises, separating such constituents by extracting the oil with chloronitroethane.
25. 11. The process of solvent refining of petroleum oils containing paraffinic and non-paraffinic constituents which comprises separating such constituents by extracting the oil with chloronitropropane.
12. The process of solvent refining of petroleum oils containing paraffinic and non-paraffinic constituents which comprises, separating such constituents by extracting the oil with chloronitrobutane.
13. The process of solvent refining of petroleum oils containing paraffinic and non-paraffinic constituents which comprises, separating such constituents by extracting the oil with B-chloro a-nitro propane.
14. The process of solvent refining of pyrogenetically produced oil fractions containing paraffinic and non-paraffinic constituents which comprises, selectively extracting the non-paraffinic constituents with a chloronitroparaffin.
15. In the process of solvent refining of pyrogenetically produced oil fractions containing paraffinic and non-paraffinic constituents the step 20 consisting in separating the constituents by extracting with a selective solvent containing a nitrochloroparaffin.
